CHANCE CONTROLLED GAME BOARD
APPARATUS WITH CARDS AND DICE

Durrel E. Post, Gates Mills, Ohio

Application July 19, 1946, Serial No. 684,889

2 Claims. (Cl. 273—135)

1

This invention relates to a game board apparatus, and particularly to a game apparatus which may be played indoors and which will simulate a king's pageant. These, therefore, are the general objects of the invention.

It is an object of this invention to provide a game board apparatus which will furnish fun and entertainment for a number of players, say from two to twelve. The invention is fully explained in the following description in connection with the accompanying drawings which set forth the game board and other apparatus, such as cards, and a chance-determining element or elements as, for instance, die or the like.

In the drawings, which are lined for color, Fig. 1 is a plan view of the improved game board; Fig. 2 is a fragmentary plan view of the game board illustrating a game in progress; Figs. 3 and 4 illustrate a series of cards used in the playing of the game; Fig. 5 is a perspective view of one form of chance-determining element represented as a die; Fig. 6 is a diagrammatic illustration of the die shown in Fig. 5; Fig. 7 is a view similar to Fig. 6 but illustrating a different die; Figs. 8 to 12 inclusive are views illustrating other dice or markers used in connection with the game; Fig. 13 is a view of a marker, and Fig. 14 is a view illustrating a different form of chance-determining element.

The game board 11, as shown in Figs. 1 and 2, is constructed in simulation of a central platform or dais 12 surrounded by a series of peripheral bands 14 which simulate a series of tiered steps surrounding and leading to the platform. Each of the bands or steps 14 is distinguished from the others and from the central platform 12 by suitable markings or, as shown, by being differently colored. The platform 12 is provided with a plurality of indicia representing the positions of various personages taking part in the pageant. In the center of the platform is a king's position which may be represented by a golden seal 16 or by a crown. The platform also is provided with two positions 18 for occupancy by heralds. These positions comprise, as shown, green colored squares. Two blue colored squares or positions 19 for pages are provided, and a jester's position 21 is indicated by a varied colored square.

The peripheral steps or bands 14 of color encircling the platform 12 are broken by colorless areas 22. These areas are aligned to simulate paths or approaches reaching from the perimeter of the board to the platform 12. As illustrated, there are four such paths or approaches 23, 24,

2

26 and 27. One of these approaches, as for instance the approach 27, is called the king's approach and is provided with a distinguishing band 28 of different color which leads to the platform. As shown in the drawings, the band 28 and the platform 12 are both represented as being royal purple.

A plurality of sets of cards are used in the game. These are indicated at 30 in Figs. 3 and 4. 10 Each set of cards includes a card of a color corresponding to the color of each step 14. The cards are preferably substantially the same size as the colorless areas 22 of such steps or bands to the end that they may be placed on and cover such area, thus completing filling the band with color. These cards represent guards and carry on their underfaces indicia for use in point scoring of the game as, for instance, five points, ten points, fifteen points, twenty points, twenty-five points, fifty points and seventy-five points respectively. The card 30A of Fig. 4, on the reverse side of which has the indicium representing seventy-five points, comprises a white card with a royal purple square. There is no colorless 25 space 22 on the bands for these cards, instead, however, they are placed directly on the platform at the end of the approaches, as indicated in Fig. 2.

In the game, as shown, I have provided eleven 30 bands of color surrounding the platform, and hence twelve cards in each set. When the game is played with two players each player is apportioned three sets of guard cards 30; for three or four players, two sets of cards 30; and from five 35 to twelve players, one set of cards 30. Thus there are always in the game more cards than there are spaces 22 for them to occupy.

There is also provided a plurality of dice or other chance-determining elements. As shown, 40 I provide two dice 31 and 32 (Figs. 5, 6, and 7) called "guard dice." The sides of these dice, as shown, are colored to correspond with the colors of the cards 30 and the steps 14. Two guard dice are used when the board is provided with 45 eleven bands 14. Thus, there is one face of a die for each card or color. When a board 12 having five bands 14 is used only the six sets of cards of Fig. 4 and the die 31 of Figs. 5 and 6 are used.

50 The die 33, shown in Fig. 8, is the "king's die." One face of this die has a golden seal 16 or crown impressed thereon. All other faces, such as that indicated at 34, are plain and are colored, as indicated purple. Fig. 9 illustrates a "herald's die" 35 provided with a golden trumpet 36 on

one face, the remainder of the die being colored green as indicated at 37. The die 38 shown in Fig. 10 represents a "page" and is colored blue with a golden salver 39 marked on one side. The die 40, shown in Fig. 11, is variably colored and is provided on one side with a jester's cap 41. The die 42, shown in Fig. 12, is white and one face is provided with a red heart 43. The game also contemplates the use of a plurality of red pasteboard or hearts or markers 44.

In playing the game, any of the dice of Figs. 8 to 12 inclusive may be used as markers, or any other marker, such as pasteboard with the indicium represented thereon, may be used in their place. The elements of chance may comprise a card, such as that shown at 45, provided with pivoted arrows 46 which may be spun so as to indicate color come to rest on a color area 47 or an indicium 48 on the card and thus take the place of the dice as the chance-determining elements of the game.

In the play of the game, each player is provided with a number of guard cards 30, heretofore indicated, such number being dependent upon the number of players in the game. The player starting the play, rolls one of the guard dice 31 or 32 together with one of the herald dice 35 bearing the golden trumpet 36. If the face of the die bearing the golden trumpet comes up, he stations that die or a suitable marker on the herald's position 18 in the center platform 12, and he also places a card, indicated by the uppermost color of the guard die which he selects to use, on any one of the approaches 23, 24 or 26. This card is placed upon the steps 14 having the same color. The play then passes to the next player who also throws a guard die 31 or 32 and a herald die 35, and should he be successful he will position the herald die or a suitable marker on the herald's position 18 of the platform 12 and a guard card on a correspondingly colored step 14. The next player would play a guard die and the king's die 33, and should he be successful would position the king die 33 or a suitable marker on the king's position 16 of the platform 12, and position a guard card 30 on a corresponding step 14.

Following the positioning of the king on the platform, the page positions 18 are filled and then and jester's position 21 is filled. The page die 38 and jester's die 40 are thrown together with a guard die, as heretofore described in connection with the herald's die 35 and king's die 33. At any time, should a player be unable to play a guard card 30 because of the occupancy of all correspondingly colored stations on the approaches 23, 24 and 26, he must pass his turn and await such time as he may have an opportunity to play one of his remaining guard cards.

The guards 30 may not be played onto the approach 27, namely, the royal approach, until the king and his entire company, namely, the heralds, the pages, and the jester are all positioned upon the platform 12, after which the approach 27 may be filled with cards 30 by the throwing of the guard dice.

After all of the approaches, including the approach 27, have been filled, the hearts 44 are presented to the king. A specific number of hearts are provided in the game say, for instance, six. The players roll the heart die 42 until the hearts 44 are all presented to the king; i. e., placed upon the platform, after which the game is at an end.

It is obvious that inasmuch as there are more 75

guard cards 30 than there are positions on the platform, some will be left. Accordingly, the score must vary. Different points are awarded for positioning the king, the jester, the pages, and the heralds, and hearts on the platform. For instance, sixty points may be awarded for the herald, seventy for the pages, eighty for the jester, and one hundred for the king. These are kept track of as they are played. If desired, the 10 dice themselves may be used as markers, two herald dice and two page dice being used. However, they may be merely represented as markers with the number of the score upon the reverse side.

15 At the end of the game the score is determined by the number of hearts and the men positioned on the central platform by each player and to this score may be added the number of points the player has secured by positioning his guards 20 on the platform. This latter number is readily estimated inasmuch as the total number of points for one set of guard cards 30 of each color is two hundred and fifty. Accordingly, if each player has two cards of each color, he had originally 25 five hundred points to start with. Deducting the number of points represented by the cards he has left in his hand when the game is finished he can readily ascertain the number of points played. However, he may total the number of 30 points on the cards each player has left, and use this total as a penalty deducting it from the point score he may otherwise have, thus ascertaining the winner of the game.

I claim:

35 1. A game apparatus comprising a rectangular game board having a rectangular central platform zone provided with a plurality of positions each having a distinguishing designation, a plurality of rectangular bands of equal width successively surrounding said central zone and varying from said zone and from each other in color, a plurality of colorless areas of equal size on said bands forming four colorless paths extending from the perimeter of the board substantially across said bands to the central zone, a plurality of sets of 40 cards of substantially the same size as said colorless areas, each set of cards including one card corresponding in color with the color of each of said bands whereby when a card corresponding in color with a band is placed on the colorless area of such band the coloring of the band will be completed, there being a greater number of sets of cards than there are paths of colorless areas, a second set of cards having designations thereon corresponding to the designations of the 45 positions on said central zone, and a chance-indicating means having a position colored to represent each card of a set, and a chance-indicating means having designations corresponding with the designations of the positions in said central zone.

2. A game apparatus comprising a rectangular game board having a rectangular central platform zone provided with a plurality of positions each having a distinguishing designation, eleven rectangular bands of equal width successively surrounding said central zone and varying from said zone and from each other in color, a plurality of substantially colorless areas of equal size on said bands forming four substantially colorless paths extending from the perimeter of the board to the central zone and substantially across each of said bands midway between the sides of the board, one of said paths having a designation to distinguish it from the other paths, a

plurality of sets of cards of substantially the same size as said colorless areas, each set of cards including one card corresponding in color with the color of each of said bands whereby when a card corresponding in color with a band is placed on the colorless area of such band the coloring of the band will be completed, there being a greater number of sets of cards than there are paths of colorless areas, a second set of cards having designations thereon corresponding to the 10 designations on said central zone, and a pair of chance-indicating elements each having six die positions there being a die positioned colored corresponding to each of said bands and said central zone, and a second set of chance-indicating elements each equaling in number the number 15 of distinguishing designations on the central zone, and each having the same number of positions as the elements of the first named pair, and each having one of its positions provided with a designation corresponding to a respective designation on the central zone and its other positions without designations.
